COLLAPSIBLE CELLULAR CARTON

William H. Inman, Newark, N. Y., assignor to
Bloomer Bros. Company, Newark, N. Y., a corporation of New York

Application May 8, 1948, Serial No. 25,877

1 Claim. (Cl. 229—28)

1

This invention relates to collapsible cartons made of cardboard or other foldable material and, more particularly, to the cellular variety thereof adapted for holding eggs, fruit, cakes and other fragile articles, one object of the invention being to provide an improved carton of this character having a more rigid, economical and convenient construction and mode of operation.

Other objects, more particularly stated, are to provide a carton of this nature having a construction in which parts of the blank, after being cut and scored, are temporarily held flat in the plane of the wall from which they are cut so as to avoid the engaging or snagging of the parts of one blank with those of another and thus prevent the injury of such parts and the entanglement of the cartons and the clogging of the machinery during manufacture and during the subsequent handling of the cartons; to provide a carton so constructed as to insure accurate folding, positioning and interengagement of the parts during the erection of the carton and thereby increase its rigidity and strength, and to provide a carton having the above advantages in a construction which is capable of being readily manufactured at relatively low cost.

To these and other ends the invention resides in certain improvements and combinations of parts, all as will be hereinafter more fully described, the novel features being pointed out in the claim at the end of the specification.

In the drawings:

Fig. 1 is a plan view of a cardboard blank cut and scored for folding to form a carton embodying the present invention;

Fig. 2 is an enlarged, fragmentary plan view of the parts after being folded and glued and in partially erected condition before swinging the transverse partitions to upright position;

Fig. 3 is an end elevation of the erected carton with the cover shown in open position in full lines partly broken away and shown in its closed position in broken lines;

Fig. 4 is a view similar to Fig. 2, but showing the transverse partitions swung to upright position;

Fig. 5 is a fragmentary, plan view of the carton in collapsed condition, and

Fig. 6 is an enlarged elevation of one end of the collapsed blank.

The preferred embodiment of the invention, herein disclosed by way of illustration, comprises a one-piece blank, indicated generally at 10, having, in order, a cover flap 11, cover 12, rear side wall 13, rear bottom section 14, longitudinal par-

2

tition portions 15 and 16, front bottom section 17, front wall 18, transverse partition wall 19, and attaching strip 20.

Cover flap 11 is provided with a series of hooks, as 21, for engagement with gusset parts hereafter described on the front wall 18, for holding the cover in closed position. The blank is scored along lines 22 and 23 to facilitate accurate folding of the flap relative to the cover 12 and of the cover 12 relative to the rear side wall 13. Heavier score lines 24 and 25 are provided for folding the side walls 13 and 18 upwardly relative to the bottom sections 14 and 17. Bottom section 14 has formed therein a series of longitudinally spaced, U-shaped cuts, as 26, connected by score lines 27 along which the longitudinal partition section 15 is folded upwardly as shown in Fig. 3, the cuts 26 producing feet 28 which are thereby thrown downwardly to hold the inner edge of the bottom section in elevated position relative to a support, for cushioning the contents of the container. The bottom section is further formed at each of these feet with a pair of L-shaped cuts, 29 and 30, to provide a flexible flap 31, for purposes hereafter described.

The bottom sections 15 and 16 are divided by a central, longitudinal score line 32, along which these sections are reversely folded to lie in juxtaposed relation against each other as they are folded upwardly from the bottom sections along score lines, as 27, to provide the central, longitudinal partition, as hereafter described. These bottom sections are also cut to provide a longitudinally spaced series of notches 33 with intervening standards or posts 34. The other bottom section 17 is cut and scored to produce the same folding score line 27 and the same series of feet 28 and associated parts as described above in connection with the other bottom section 14.

The front wall 18 is foldably connected at its top with the transverse partition wall 19, which is cut and scored to produce a longitudinally spaced series of transverse partitions 35. To this end, each partition is severed from the front wall 18 along intersecting lines 36 and 37, leaving between adjacent partitions a space 38 which is left unsevered but marked off by a score line 39 to control bending at this space in a straight line joining the ends of the adjacent cuts 36 and 37 of adjacent partitions as shown in Fig. 2. Openings 40 are cut to separate adjacent partitions so that they are formed with upper edges 41 and lower edges 42. A score line 43 in line with beyond each end of upper edge 41 controls bending in a straight line extending between the end

of the upper edge of each partition and the end of the adjacent cut 36, forming the substantially triangular gussets 44 enclosed by the score lines 37, 39 and 43 and the ends of the openings between the partitions, as shown and for the purposes hereafter described.

The other ends of the transverse partitions 35 and the attaching strip 20 have formed therebetween the same cuts and score lines as described above between the other ends of the partitions and the front wall 18 and each partition 35 has its lower edge 42 shaped to produce a central projecting portion 45. Each partition has a central cut 46 extending inwardly through this projecting portion and the material is scored along lines 47 at opposite sides of this cut to make its sides flexible. Cuts 46 extend part way across the partitions and the remaining portion of the material is scored as at 48 to enable each partition to be folded centrally on itself in the collapsed position of the carton, as shown in Figs. 5 and 6 and hereafter described.

It is to be noted that each end of the lower edge 42 of each partition is left connected with the adjacent gusset 44 by a narrow web of material 49 lying between the end of the cut 36 and the opening 40 between partitions. This web is wide enough to afford a substantial connection between the corners of the partitions and the gussets, while being readily frangible by pressing the lower portions of the partitions downward for swinging them to upright position. During the erection of the carton and before being broken to swing the partitions upright, these webs maintain a sufficient continuity of the transverse wall comprising the partitions, longitudinally and transversely of the carton, to pull it, including the gussets 44, to a substantially flat and horizontal position folded about the longitudinal score lines 39. This accurate folding and positioning of the gussets provides an accurate hinge axis through the score lines 43, to insure accurate and symmetrical engagement of the partitions with the posts 34 of the longitudinal partition and precise and reliable engagement of the projecting portion 45 of each partition in the bottom openings left by the down-turning of the feet 28, as well as accurate spacing of the front and rear walls. The frangible connection of the ends of the bottom edges of the transverse partitions with the sides of the gussets opposite the hinge lines 43, rather than with the side walls of the carton, has the further advantage that, in swinging the transverse partitions downwardly before filling the cells, they may be cleanly broken away from the gussets without any peeling of the cardboard surface as would be the tendency if the frangible webs 49 were connected to the tops of the side walls of the carton.

In the known construction in which the partitions have been severed from the gussets in the cutting of the blank, the gussets have been left without sufficient connections to insure their accurate folding to horizontal position and the subsequent swinging of the transverse partitions to upright position has tended to hinge them about indefinite and variable fold lines tending to cross the gussets intermediate the score lines 39 and 43, with the result of improper positioning of the partitions and insecure engagement thereof with the longitudinal partitions and with the openings in the carton bottom. By the means of the present invention, an accurate shaping of the erected carton is obtained, as well as the

secure interengagement of its transverse and longitudinal partitions for securing the parts closely in their intended positions and maintaining the rigidity of the carton.

In the folding and gluing of the carton, the blank is preferably folded to bring together the longitudinal partition portions 15 and 16 which are glued to each other. The front wall and transverse partition wall are folded against these portions and the rear half of the transverse partitions are folded about the lines 46 and 48 over the posts 34 which are thus projected through the lines or cuts 46 of the partitions. The attaching strip 20 and the rear wall 13 are then brought and glued together, the blank being thus disposed in the flat collapsed position shown in Figs. 5 and 6 in which the webs 49 hold the transverse partitions in the plane of the material so as to prevent the partitions from projecting and snagging the machine parts during manufacture and the cartons from becoming entangled with one another during subsequent handling.

In the erection of the carton for use, the bottom sections 14 and 17 are separated, the longitudinal partition being maintained in upright position by the engagement of its posts 34 in the cuts 46 of the transverse partitions, the latter being pressed downwardly to substantially horizontal position. Such unfolding of the blank spreads or forces the side walls apart to their substantially upright, erected position, the inner edges of the bottom sections being held elevated by the feet 28 depending from the longitudinal partition, so as to elevate the inner portions of these sections to cushion the carton contents. The transverse partitions and their gussets being thus brought to substantially flat horizontal position, as described above, the lower edges of the partitions are pressed downwardly to break the webs 49 and swing the partitions to upright position. The proper positioning, as described, of the gussets and partition hinges, insures precise interengagement of the notches of the transverse and longitudinal partitions and of the projecting portions 45 of the partitions in the openings in the bottom sections left by the down folding of the feet 28. The flexible flaps 31 at the sides of these openings facilitate the downward folding of the feet and entry into the openings of the projections 45 on the lower edges of the partitions. After filling the cushioned cells thus produced, the cover is folded over about the score lines 22 and 23 and the hooks 21 of the cover flap are engaged beneath the gussets at the top of the front wall to connect the cover in the closed position while supported at its center by the longitudinal partition.

It will thus be seen that the invention accomplishes its objects and while it has been herein disclosed by reference to the details of a preferred embodiment, it is to be understood that such disclosure is intended in an illustrative, rather than a limiting sense, as it is contemplated that various modifications in the construction and arrangement of the parts will readily occur to those skilled in the art, within the spirit of the invention and the scope of the appended claim.

I claim:

A cellular carton in collapsed form made of foldable blank material comprising longitudinally extending, transversely spaced side walls, a bottom wall foldable about the longitudinal center line thereof and having its side edges foldably

connected with the bottom edges of said side walls, respectively, a transverse partition wall foldable about the longitudinal center line thereof and cut and scored to form a series of longitudinally spaced, transverse partitions and substantially triangular gussets foldably connected with the ends of the upper edges of said partitions and with the upper portions of said side walls and forming a hinge along one side of each of said gussets about which said transverse partitions may be swung to upright position to divide the space between said side walls into a series of longitudinally spaced cells, said partitions each having each end of the lower edge thereof connected by a frangible web with the adjacent gusset of the adjacent partition on the side of the gusset opposite said hinge, to maintain the lower edges of said partitions in the planes of said side walls in the collapsed position of said carton and

to swing said gussets to a flat horizontal position about the folding connections thereof with said side walls to maintain the accurate spacing and positioning of said side walls and partitions in the erected condition of said carton, said webs being readily frangible for swinging said partitions to upright position.

WILLIAM H. INMAN.
